Primary Examiner — Kevin Rudzinski*Assistant Examiner* — Kathleen Jones(74) *Attorney, Agent, or Firm* — Westerman, Hattori,
Daniels & Adrian, LLP(57) **CLAIM**

The ornamental design for an automobile tire, as shown and described.

DESCRIPTION

FIG. 1 a front view of an automobile tire;
 FIG. 2 is a rear view thereof;

FIG. 3 is a top plan view thereof, for which the bottom plan view is the same;

FIG. 4 is a right-side view thereof;

FIG. 5 is a left-side view thereof;

FIG. 6 is a perspective view thereof;

FIG. 7 is an enlarged cross sectional view along line 7-7 in FIG. 1, in the area designated by "7" in FIG. 4 thereof; and, FIG. 8 is an enlarged sectional view taken along line 8-8 and line 8'-8' in FIG. 1.

In the drawings, the broken lines defining the sidewall, inner bead and the peripheral boundary between the tire tread shown in solid lines and the sidewall shown in broken lines depict environmental subject matter that forms no part of the claimed design.
